UNITED STATES PATENT OFFICE

CHARLES N. WRENSHALL, OF ASHEVILLE, NORTH CAROLINA

EYESHIELD

Application filed May 29, 1930. Serial No. 457,187.

The present invention relates to new and useful improvements in eye shields and has for its primary object to provide, in a manner as hereinafter set forth, a device of this character embodying novel means for preventing perspiration from running into the eyes of a wearer of the device.

Another important object of the invention is to provide an eye shield of the character described including a visor and a head encircling bandreau for supporting said visor in position on the head of the wearer, the device further embodying a novel construction and arrangement for connecting the bandreau to the visor in such a manner that said bandreau will function as a perspiration absorbing pad.

A further important object of the invention is to provide an eye shield of the character set forth wherein the bandreau is detachably connected to the visor for the purpose of permitting the same to be expeditiously removed when it is desired to launder the same or to replace the same.

A still further important feature of the invention resides in the provision of means for mounting the visor in position in such a manner that the body portion thereof will not come into contact with the head of the wearer, thus assuring a maximum of comfort.

Other objects of the invention are to provide an eye shield which will be simple in construction, strong, durable, efficient in its use and which may be manufactured at low cost.

All of the foregoing and still further objects and advantages of the invention may become apparent from a study of the following specification, taken in connection with the accompanying drawings wherein like characters of reference designate corresponding parts throughout the several views, and wherein:

Figure 1 is a view in top plan of an eye shield constructed in accordance with this invention with a bandreau mounted thereon.

Figure 2 is a detail view in elevation of the bandreau.

Figure 3 is a detail view of the bandreau showing the same in edge elevation.

Figure 4 is a cross sectional view taken substantially on the line 4-4 of Figure 1 with the bandreau removed from the visor.

Referring to the drawings in detail, it will be seen that the reference numeral 1 designates a visor which may be of any desired configuration and which is to be formed of any suitable material. The visor 1 is preferably formed to conform substantially to the forehead of the wearer and has formed on its inner marginal portion a plurality of spaced eyes or loops 2. As illustrated in the drawings the eyes or loops 2 are of circular configuration and formed integrally with the visor 1 but it is to be understood that said eyes may be of any desired configuration and formed of separate pieces to be attached to the visor.

It is further understood that any desired number of the eyes may be provided and the same may be disposed at any desired point on the visor 1.

The eyes or loops 2 are for the passage of a head encircling supporting bandreau 3 which, in the present instance comprises a strip of flexible material of appropriate width and length which is folded upon itself intermediate its ends and inserted through the eyes 2. The folds of the bandreau may be stitched together along their longitudinal marginal portions from the free ends thereof to a point in spaced relation to the fold line thereof as indicated at 4 and in a manner to provide a loop 5 through which the stitched together free end portions of said bandreau are inserted in the manner illustrated in Figure 1 to secure said bandreau around the head of the wearer.

In use, the bandreau 3 is engaged with the head of the wearer and will thus absorb perspiration thereby preventing said perspiration from running down into the eyes, it being understood, of course, that the bandreau is of a suitable absorbent material. It will further be readily apparent that the visor 1 will be securely supported in position in spaced relation with respect to the head of the wearer and that only the eyes 2 will contact with the wearer's head. When it is desired to remove the bandreau from the visor

for laundering or replacing the same it is only necessary to slide said bandeau out of the eyes 2. The visor and the bandeau are preferably in attractive colors or a combination of 5 colors and, if desired, a number of the bandeaus of various colors may be provided with each visor in order that a choice of the combination of colors may be had.

It is believed that the many advantages of 10 an eye shield constructed in accordance with this invention will be readily understood, and although the preferred embodiment of the invention is as illustrated and described, it is to be understood that changes in the 15 tails of construction may be had which will fall within the scope of the invention as claimed.

What is claimed is:—

1. An eye shield of the character described 20 comprising a visor, a series of eyes mounted on one marginal portion of said visor and projecting therefrom, and a strip of flexible, moisture absorbing material extending through the eyes and constituting means for 25 supporting the visor on the head of a wearer.

2. An eye shield of the character described comprising a visor, a series of eyes on one marginal portion of said visor in spaced relation with respect to each other, said eyes 30 projecting from the visor, and a flexible strip of moisture absorbing material removably disposed through the eyes and constituting means for supporting the visor in position 35 on the head of a wearer in spaced relation to said wearer's head.

3. An eye shield of the character described comprising a visor, a series of spaced, integral eyes on one marginal portion of the visor and projecting therefrom, and a flexible 40 strip of moisture absorbing material removably disposed through the eyes for encircling the head of a wearer and constituting means for supporting the visor in position thereon in spaced relation thereto.

4. An eye shield of the character described comprising a visor having an arcuate edge conforming substantially to the head of a wearer, a series of integral eyes mounted integrally on the arcuate marginal portion of 50 said visor and projecting therefrom, and a flexible strip of moisture absorbing material removably inserted through the eyes and adapted to encircle the head of the wearer in a manner to support the visor in position 55 thereon in spaced relation thereto.

5. An eye shield of the character described comprising a visor having an inwardly curved edge, a series of integral eyes mounted in spaced relation with respect to each other 60 on the inwardly curved marginal portion of the visor and projecting therefrom, and a head encircling band of flexible, moisture absorbing material removably inserted through the eyes and engageable with the forehead of 65 the wearer in a manner to absorb moisture

therefrom, said strip further constituting means for mounting the visor in position on the forehead of the wearer in spaced relation thereto.

6. An eye shield of the character described 70 comprising a visor, a plurality of eyes on one marginal portion of said visor and projecting therefrom, and means for supporting the visor in position on the head of a wearer, said means comprising a strip of flexible, 75 moisture absorbing material folded upon itself and removably inserted through the eyes, said strip adapted to encircle the head of the wearer and having a loop formed at the fold line thereof for connecting the end portions 80 of said strip thereto.

7. An eye shield of the character described comprising a visor, a series of eyes on one marginal portion of said visor projecting therefrom, and means for securing the visor in position on the head of a wearer, said means comprising an elongated strip of flexible moisture absorbing material folded upon itself intermediate its ends, the folds of said strip stitched together from the opposite ends 90 thereof to a point in spaced relation to the fold line in a manner to provide a loop, said folded strip removably inserted through the eyes and adapted to encircle the head of the wearer, said loop adapted for the passage of 95 the free end portion of the strip in a manner to secure said strip in position about the wearer's head.

In testimony whereof I affix my signature.

CHARLES N. WRENSHALL.
